UNITED STATES PATENT OFFICE.

PAUL E. BRENEMAN, OF DETROIT, MICHIGAN, ASSIGNOR TO THE STUDEBAKER CORPORATION, OF SOUTH BEND, INDIANA, AND DETROIT, MICHIGAN, A CORPORATION OF NEW JERSEY.

TOP CONSTRUCTION.

Application filed March 17, 1926, Serial No. 95,315. Renewed January 10, 1927.

This invention relates to vehicle bodies of the enclosed type, and particularly to improvements for the tops thereof, the main object being to provide a new and novel 5 side rail construction therefor, which will be easy to assemble, light in weight and economical to manufacture.

Another object is to provide a top for a closed vehicle body, with side rails composed 10 of sheet metal longitudinal side members and wooden longitudinal tacking members.

A further object is to provide a vehicle 15 top of the permanent type with a hollow metallic side rail comprising longitudinal frame and shaping members rolled together along the outer edges thereof to provide a drip trough and secured along the inner edges thereof to a common tacking strip of wood, the frame member being 20 shaped to provide a suitable door stop.

These being among the objects of the present invention, the same consists of certain features of construction and combinations of parts to be hereinafter described 25 with reference to the accompanying drawing, and then claimed, having the above and other objects in view.

In the accompanying drawing which 30 illustrates a suitable embodiment of the present invention, and in which like numerals refer to like parts throughout the several views:

Figure 1 is a perspective view showing a portion of a vehicle body having a permanent type top attached thereto which is provided with side rails embodying the present 35 invention.

Figure 2 is an enlarged perspective sectional view of one of the side rails taken 40 transversely thereof adjacent one of the top cross-struts.

Figure 3 is a transverse sectional view of one of the side rails taken longitudinally through one of the cross-struts, showing the 45 method of securing the same to the side rail.

Figure 4 is a fragmentary plan view of one of the cross-struts and tacking strip.

Figure 5 is an enlarged fragmentary sectional view more clearly showing the con-

nexion between the side rail and one of the cross-struts.

The top, as shown in Figure 1 has the shape of the usual type of permanent top and is suitably supported by the back panel 55 11 and pillars 12 which are embodied in the vehicle body. The top structure is built up as a unit to consist of a pair of spaced hollow sheet metal side rails 13, spanned by a number of regularly spaced cross-struts 14, 60 a front end member 15 and a rear end member 16.

Each side rail 13 as illustrated in Figures 2 and 3, is composed of two main members, herein called a base member and a top side 65 quarter member 18, and common longitudinal tacking strips 19. Both the base member and side quarter member 18 are of sheet metal and may be very economically produced by stamping from single sheets of 70 suitable metal.

The base member is, in reality, the support for the complete top on the vehicle body and is shaped with a horizontal portion 20, to which the body pillar brackets 75 and the like (not shown) are secured, having an upwardly extending marginal flange 21 formed along the outer edge thereof. The metal at the inner edge of the horizontal portion 20 is bent downwardly, then 80 curved substantially back upon itself to provide a downwardly projecting door stop 22 and continues upwardly to provide a vertical wall 23 terminating in a wide horizontal inwardly turned flange 24.

As previously stated, a plurality of regularly spaced cross-struts 14 extend transversely between the side rails 13, the ends thereof being supported by and secured to the upper surface of the flange 24 of the 90 base member. These cross-struts are preferably of sheet metal and trough shaped in form, the sides having outwardly flanged upper edges 25. It will be seen, however, that they may be of any other shape and may 95 be made of some material other than sheet metal. Longitudinally extending tacking strips 19, mentioned heretofore are positioned on the horizontal flange 24 of the base member and extend from the side of 10.

one cross-strut 14 to the side of the adjoining one, small wooden blocks 26 being inserted in the trough of each cross member to effect a continuation of the same. Nails 5 or screws 28 hold the tacking strips 19 in place on the flanges 24, and the cross-struts 14 may be held in place thereon only by the screws 27 which pass up through the flange 24 and into the block 26 for holding the 10 same in place, or may be firmly secured by welding the same thereto, depending on the rigidity desired.

The side quarter member 18 lends a neat and more finished appearance to the side 15 of the top as well as imparting strength thereto, and is preferably coved or formed with a rounded surface as shown in the drawings. The lower or outer edge of the side quarter member 18 extends horizontally 20 outwardly for a slight distance and terminates in an upwardly extending marginal flange 30 which provides a longitudinal trough 29 between it and the main body of the quarter member for catching all water 25 and rain which drips from the top and guides it to the rear end thereof where it is discharged. The side quarter 18 is rigidly secured along its outer edge to the base member by turning the edge of the flange 21 over and clamping it against the upstanding 30 leg 30 of the trough 29.

Conventional top constructions of the past used a combination molding and drip trough longitudinally secured along the sides thereof to catch the water and rain which dripped therefrom. The trough 22 just described, successfully eliminates the necessity of such a separate trough and molding, thereby providing a much more economical 40 and desirable construction.

The upper or inner edge 31 of the quarter member 18 extends over to lie on the upper faces of the tacking strips 19, tongues 33 being formed on the extreme edge thereof 45 which are welded to the flanged edges 25 of the cross-struts 14.

Suitable top covering 34 covers the structure and is tacked to the tacking strips 19, a molding 35 of suitable design also being 50 secured to the tacking strips 19 to conceal the edge of the top covering and to give a more finished appearance to the entire structure.

From the foregoing description, it will be 55 seen the present construction has marked advantages over constructions previously used, and that it is simple and economical to manufacture and assemble and light in weight.

60 Formal changes may be made in the specific embodiment of the invention described without departing from the spirit and substance of the broad invention the scope of which is commensurate with the appended 65 claims.

What I claim is:

1. A vehicle top comprising hollow metallic side rails, each having a Z-shaped base member and a rounded quarter member, spaced trough-shaped cross-struts holding 70 said side rails in spaced relationship, tacking strips positioned between the free ends of said base and quarter members intermediate said cross-struts, and tacking blocks positioned in the troughs of said cross-struts to effect a continuation of said tacking strips. 75

2. In a vehicle top of the permanent type, spaced side rails, each comprising a Z-shaped metallic base member and a coved 80 metallic quarter member secured together along their outer marginal edges to provide a drip trough and spaced at their inner edges, sheet metal cross-struts secured to both said base members and said quarter members between the free ends thereof, and tacking strips also secured between the free 85 ends of said base members and quarter members intermediate said cross-struts.

3. In a permanent type vehicle top, Z- 90 shaped sheet metal base members, trough-shaped cross-struts secured at intervals to the inner marginal edge of each of said base members, tacking members positioned on said edge to extend between said cross-struts, blocks positioned in the troughs of said cross-struts to effect a continuation of said tacking members, and rounded sheet metal side quarter members secured along their outer edges to the outer edges of said base members and secured along their inner edges to both said 95 tacking members and said cross-struts. 100

4. In a vehicle top of the permanent type, Z-shaped metallic base members, door stops formed integral with said base members by 105 bending a portion of the metal thereof downwardly and back upon itself, cross-struts secured at intervals to the inner marginal edge of said base members, tacking strips secured to said marginal edges between said cross-struts, and side quarter members secured along their outer edges to the outer marginal edges of said base members and secured along their inner marginal edges to both said tacking strips and said 110 cross-struts, said cross-struts and said tacking strips holding said inner edges of said base and quarter member in spaced relationship. 115

5. In a vehicle top of the permanent type, 120 spaced side rails, each comprising a metallic base member and a coved metallic quarter member secured together along their outer marginal edges to provide a drip trough and spaced at their inner edges, cross-struts secured to the free edges of said base member and said quarter member, and tacking strips secured to the free edges of said base member and quarter member intermediate said 125 cross-struts. 130

6. In a vehicle top of the permanent type, sheet metal base members, cross-struts secured at intervals to the inner marginal edge of each of said base members, tacking members positioned on said edge to extend between said cross-struts, and rounded sheet metal side quarter members secured along their outer edges to the outer edges of said base members and secured along their inner edges to both said tacking members and said cross-struts. 15

5

7. In a vehicle top of the permanent type, sheet metal base members, trough-shaped cross-struts secured to the inner marginal edge of each of said base members, tacking members secured to said edge of said base members between said cross-struts, blocks secured in the troughs of said cross-struts to effect a continuation of said tacking members, and rounded sheet metal side quarter members secured along their outer edges to the outer edges of said base members and secured along their inner edges to both said tacking members and said cross-struts. 20

Signed by me at Detroit, Michigan, U. S. A., this 12th day of March, 1926.

PAUL E. BRENEMAN.
